UNITED STATES PATENT OFFICE.

ABRAHAM NOVICK, OF NEW YORK, N. Y., ASSIGNOR TO F. L. SMITH MACHINE CO., INC., OF NEW YORK, N. Y., A CORPORATION OF NEW YORK.

WASHER AND STRING ATTACHING MACHINE.

1,370,551.

Specification of Letters Patent.

Patented Mar. 8, 1921.

Application filed February 17, 1920. Serial No. 359,383.

To all whom it may concern:

Be it known that I, ABRAHAM NOVICK, a citizen of the United States, and a resident of the city of New York, in the county of New York and State of New York, have invented certain new and useful Improvements in Washer and String Attaching Machines, of which the following is a specification.

10 This invention relates to machines for attaching washers and string to envelopes, and is especially applicable to that type of machine which limits the function of the operator to the insertion and the withdrawal 15 of the envelop from the machine, which automatically does the rest.

One of the objects of this invention is the provision of positive and dependable string feeding means for automatically passing 20 string through a washer for stringing said washer.

A further object of this invention is the provision of automatic, adjustable means for drawing any predetermined length of string, 25 within the limits of the adjustment through the washer, whereby the length of string is automatically fed from a string support and arranged for attachment to an envelop.

A further object of this invention is the 30 provision of automatic means for feeding the washer and the string into the setting position.

A further object is the provision of automatic means for severing the string at the 35 proper time without attention being given thereto by the operator.

Still further objects will be apparent from the description which follows, since the primary purpose of my invention is to 40 make automatic all of the operations for attaching the washer and string to the envelop, except the operation of inserting the envelop into the machine and the withdrawal of said envelop after the string and 45 washers have been attached.

In the drawings, Figure 1 is a side view of my improved machine, and partial section on line 1—1 of Fig. 2. Fig. 2 is a front view of my machine. Fig. 3 is a vertical 50 section of the setting, forwarding and string severing mechanism on line 3—3 of Fig. 1. Fig. 4 is a similar view showing a different position assumed by the parts. Fig. 5 is a side view of the string severing mechanism. Fig. 6 is a plan view of the washer for-

warding slide. Fig. 7 is a plan view of the string gripping and withdrawing tongs, and the mechanism for causing the tongs to release the string. Figs. 8, 9 and 10 are diagrammatic sections, showing the steps in the 60 stringing, and in the washer and string forwarding operations. Fig. 11 is a plan view and partial section of the bottom washer forming and forwarding mechanism, and Fig. 12 is a side view and partial section of 65 the same. Fig. 13 is a view of an envelop to which washers and string have been attached by my machine.

For detailed descriptions of the mechanism used for attaching a washer and string 70 to an envelop by means of an eyelet, reference is made to my Patent 1,104,128 and for descriptions of the mechanism for use in forming bottom washers and for attaching them to envelopes, reference is made to my 75 Patent 1,255,558 and to the patent to Olm 1,114,177. Only a general description of the above mentioned mechanism as is used in connection with the present invention need be given hereinafter for the purpose of understanding the invention proper.

The main driving shaft 1, controlled by a one revolution clutch not shown, is driven through pulley 2 from a source of power not shown. The various submechanisms are 85 driven through cams or cranks mounted on main shaft 1 as will be hereinafter more fully described.

A bottom washer forming mechanism, similar to that shown by Patent 1,114,177 is 90 driven by cam 3 on shaft 1, through rod 4, which is connected to crank 5, loosely mounted on shaft 6. A pawl 7 pivoted on the end of rod 4, engages ratchet wheel 8 for intermittently turning shaft 6 to rotate 95 paper forwarding rolls 9 and 10 for advancing the web of paper 11 a sufficient distance at each impulse to form a square washer at the setting position, this being the term I will use to designate that point in the machine where the top washer, eyelet, string and bottom washer are assembled in proper 100 relation and the eyelet clenched to secure the washers and string to the envelop.

For forming the bottom washer 12 from 105 web 11, (Figs. 12 and 13) stationary blade 13 on an anvil 20 coacts with the edge of hollow die 14 to sever the web between them. Said die 14 is arranged to reciprocate vertically, a stationary cutting pin 15 coacting 110

with said die to cut a hole in web 11 in the center of the next prospective washer of said web, while the first washer is being severed. For reciprocating said die, a series of connections are provided, comprising link 16, rod 17, lever 18, and cam 19, operated from shaft 1.

An eyelet supplying chute 21 is pivoted to upper frame 22 at 23, and is arranged to be oscillated by means of cam roller 24, which is fastened to vertically reciprocating shaft 25 by a split collar as 26, and which engages cam 27 on said chute. The timing of the parts is such that an eyelet as 28 is brought into setting position at about the same time that a top washer and bottom washer are brought to that position in a manner known in the art.

The setting or clenching of the eyelet is accomplished by the usual mechanism used for that purpose, (Fig. 1) such as reciprocating shaft 25, operated through lever 32, and rod 29, from cam disk 30 on shaft 1, said shaft 25 carrying pilot needle 31 and eyelet flanging die 33 in the lower end thereof. A spring 34 is placed in shaft 25 in the space above needle 31, and acts to maintain said needle normally in its extended position. On anvil 20, is provided a stationary die 35 of suitable shape to coöperate with die 33 to flange the eyelet when shaft 25 is brought down to its lowest position whereby pressure is put on the eyelet by movable flanging die 33.

The mechanism for supplying top washers 36 and for delivering them one at a time to the setting position, is supported by auxiliary frame 37 suitably attached, as by screws 138 to upper frame 22. Said frame 37 has an opening 38 therein which is used as a washer reservoir, a gate 39 adjustably secured in an opening as 40, being provided to partly close the lower side of said reservoir 38.

Frame 37 has guides 41 at the bottom thereof, slots 32 being cut in said guides to receive stepped forward slide 43. Washer ejecting member 44 shaped at its forward end at 45 to fit washer 36 is set into slide 43 so that it projects upwardly from said slide an amount equal to the thickness of one of said washers 36, to form the first step in said slide. Depression 46 at the forward end of slide 43 is cut down into said slide a distance somewhat greater than the thickness of said washer to form the second step, and is undercut at the rear portion 47 thereon to prevent the washer resting in said depression from being lifted out. A slot 48 somewhat greater in width than the diameter of the hole in washer 36 extends from the forward edge of slide 43 rearwardly a sufficient distance such that a washer in contact with edge 45 is positioned with the hole therein directly over the rear end of said slot.

For reciprocating said slide 43, lever 49 pivoted at 50 from bracket 51 of lower frame 52 and carrying cam roller 123 in engagement with the outer edge of cam 30 on shaft 1, is oscillated on the rotation of said cam 30 and in turn oscillates shaft 53 carried by brackets 54 and 55 from frame 22, through connecting link 56 and crank 57 on said shaft 53. Crank 58 mounted on said shaft 53 is connected to one end of link 59, the other end of said link being connected to post 60 suitably attached to the rear end of slide 43. Cam 30 is designed to halt the slide so that the washer carried thereby is brought to the stringing position for having a string passed through the hole thereof, and another washer is carried in depression 46 at the same time to the setting position to allow pilot needle 31 to pass through said washer, said cam also being shaped to carry said slide rearwardly to its initial position in proper time.

For supporting string tube 61 for reciprocation vertically therein, an opening 62 is made in frame 37. The lower end of string tube 61 is constricted to form string needle 63 of a diameter slightly less than that of the hole in washer 36, string 64 being threaded through said tube and needle from a suitably supported spool, not shown.

The mechanism for reciprocating tube 61 and needle 63 comprises cam 65 on shaft 1, which actuates crank 66 through cam roller 67, and lever 68 connected at one end to said crank 66 and at the other end to crank 69 on shaft 70 passing through frame 22, arm 71 being suitably mounted on that end of shaft 70 opposite to the one on which crank 69 is mounted, said arm 71 engaging tube 61 at double collar 72. Spring 77 attached at one end to rod 76 on shaft 70, and at the other end to pin 78 on frame 22, serves to take backlash out of the connections. A pair of blades 73 and 74 are provided as close as is mechanically possible to shaft 25 for severing the string 64, said blades being pivotally attached to frame 37 by means of screw 75. Springs 79 and 80 attached at one end respectively to blades 73 and 74 are connected at the other ends to pins 81 and 82 respectively, on frame 22, and serve to keep said blades normally apart, stop 83 on frame 37 acting to limit the separating movement of said blades by engaging projections 84 and 85 thereof. Collar 86 is mounted on the lower end of shaft 25, and carries two pins 87 and 88 thereon, of sufficient length to engage blades 73 and 74 respectively for pressing said blades together to sever the string between them on the downward movement of said shaft 25.

A pair of string gripping tongs 89 is carried by arm 91 which ends in cylindrical portion 92, a spring 90 acting to urge the string gripping jaws of said tongs toward

each other. Radial adjustment of tongs 89 is provided for by moving cylinder 92 in or out of hollow cylinder 93 carried by arm 94 on shaft 95, a screw 96 being arranged to hold arm 91 in adjusted position. For opening tongs 89 a finger 97, pivoted on bifurcated arm 91 at 100 and carrying cam roller 98, is disposed so that said roller 98 engages the outer edge of adjustable cam arm 101 on the rearward oscillation of arm 91. A stationary stud 104 (Fig. 1) suitably mounted in frame 22 carries stationary segment 102 having slot 103 (Fig. 7) therein, said arm 101 being adjustably fastened in slot 103 by wing nut and bolt 99, the inner end of said arm 101 being loosely mounted on shaft 95.

The mechanism for rotating shaft 95 is so designed that adjustment thereof will vary the length of only one end of the arc through which tongs 89 travel, the limiting position of the other end of said arc being the stringing position, by which I mean that the point of the machine at which a string loop is formed by string needle 63 in a manner more fully described hereinafter. Said shaft 95 is supported in bracket 105 extending from frame 22, and in segment 102, and has mounted thereon bevel gear 106. Meshing with said gear 106 is segmental bevel gear 107 supported on stud 104 for oscillation thereon. Segment 107 has slotted arm 108 extending therefrom to which is adjustably attached a hollow connecting coupling 109 by means of wing nut 30 and bolt 110 passing through slot 111, which is suitably curved. Said coupling 109 has slots 112 therein to receive pin 113 of connecting rod 114 attached to rod 115 of cam disk 30, a spring 116 being provided between rod 114 and coupling 109 of sufficient strength to keep said rod and coupling normally in the position shown in Fig. 1, said spring being designed to take up motion of rod 114 past the usual limiting position of said rod. A stop 117 on frame 22 is arranged to prevent oscillation of segmental gear 107 past a predetermined point, namely, the stringing position. Stop 118 is adjustably held in bracket 119 supported from frame 37, by set screw 120 and is arranged to strike lug 121 on finger 97 for withdrawing said finger from between tongs 89 when said tongs reach the stringing position.

The operation of my improved machine is as follows:

String tube 61 having been threaded, top washer reservoir 38 having been supplied with washers, eyelet chute 21 having been provided with eyelets, a web of paper having been drawn between rolls 9 and 10 and between die 14 and pin 15, and the envelop to which string is to be attached having been properly placed on anvil 20, pulley 2 is started revolving. Slide 43 is thereby moved from its rearmost position toward the

stringing position, member 44 removing the bottom washer of the pile, which rests on slide 43 past gate 39 into the stringing position. (Fig. 9). Tube 61 moves downwardly when said slide has been halted in the stringing position, needle 63 carrying string 64 with it through the hole in washer 36. (Fig. 10). At the same time, shaft 95 is rotated to bring tongs 89 toward the stringing position, and slide 43 is moved rearwardly. The washer is held on slide 43 by needle 63 which passes through slot 43 of said slide, whereby the washer is forwarded to depression 46. When tongs 89 in their forward oscillation are very close to the stringing position, finger 90 having been inserted between the ends of said tongs to keep the jaws thereof open, needle 63 is lifted out of washer 36, the diameter of said needle being only slightly less than that of the washer hole, string 64 is held by friction against the side of the hole while said needle is being withdrawn therefrom, and a loop in string 122 is left pendent from said washer. Immediately after the withdrawal of needle 63, the open tongs 89 reach loop 122, lug 121 of finger 97 striking stop 118 to rotate said finger about pivot 100 for withdrawing said finger from said tongs, whereby spring 90 acts to close the jaws of said tongs upon loop 122. (Fig. 8). The closed tongs are now swung rearwardly while slide 43 is advanced between blades 73 and 74 whereby a length of string is fed through tube 64, and the washer 36, which has been strung, is forwarded to the setting position with the string therethrough, said washer being prevented from lifting off slide 43 by being drawn back into the undercut part 47 of depression 46, by the pull on the string, and another washer is removed by member 44 from the pile. (Fig. 9).

As tongs 89 reach their rearmost position, shaft 25 reaches its highest position and chute 21 presents an eyelet into setting position above the forward top washer held by slide 43, the last part of the rearward motion of tongs 89 causing cam roller 98 to engage the outer edge of arm 101 to insert finger 97 between said tongs, causing them to release the string loop. At this time, die 14 is about to move down to cut off a washer from web 11. As tongs 89 again move forward, shaft 25 moves downwardly, pilot pin 31 passing through an eyelet, top washer and envelop until it comes in contact with stationary die 35. Needle 63 now passes through the washer removed from the pile by member 44 as above described, while slide 43 again moves rearwardly to leave the foremost washer on pilot needle 31, needle 63 again forms the loop 122, tongs 89 move forward to grasp the string, and shaft 25 moves downwardly until dies 33 and 35 co-

act to drive the eyelet through the top washer, envelop and bottom washer, and to flange the eyelet, (Figs. 3 and 8), a bottom washer being severed from web 11 just before the flanging takes place.

On the downward movement of shaft 25, blades 73 and 74 are operated through pins 87 and 88 and are closed to sever the string automatically before the eyelet is flanged, leaving the envelop free to be withdrawn with the washers and string of the desired length attached thereto, on the completion of the downward movement of said shaft. As the needle 31 moves out of the eyelet, the finished envelop is removed and a new one inserted, tongs 89 move rearwardly with the string loop, feeding string through the washer, and slide 43 forwards the next strung washer again to the setting position, (Fig. 9) and the operation repeated.

Adjustment of the machine for cutting strings of various lengths is obtained by moving nut and bolt 110 in slot 111, adjusting arm 101 in slot 103, and adjusting arm 91 radially.

It will be seen that the string feed is positive, and automatic, and that the string is automatically fed and cut the desired length without attention on the part of the operator.

30 What I claim is:

1. In a machine of the character described, means for stringing a washer, means for fastening said washer and the string passing therethrough to an envelop, and means adjacent to said fastening means for automatically severing said string close to said washer.

2. In a machine of the character described, means for stringing a washer comprising means for forming a free string loop pendent from the opening in said washer, and means for gripping said loop bodily for drawing a predetermined length of string through said washer.

3. In a machine of the character described, means for passing string through a washer at a point in space relation to the setting position, means for gripping said string and for drawing a predetermined length of string through said washer, and means for forwarding said string and washer to the setting position.

4. In a machine of the character described, reciprocating means for passing a loop of string through a washer at a point in space relation to the setting position, means for gripping said string and for drawing a predetermined length of string through said washer, and means for forwarding the washer with the string therethrough to the setting position.

5. In a machine of the character described, means for removing one washer at a time from a washer reservoir, and for forwarding said washer to the stringing position, and

means for stringing said washer at the stringing position and for coacting with said forwarding means for forwarding the strung washer to the setting position.

6. In a machine of the character described, means for delivering a washer and string to the setting position, and means adjacent to the setting position for automatically severing said string close to the setting position.

7. In a machine of the character described, means for fastening string and a washer to an envelop, and a pair of shears actuated by and positioned close to said fastening means for automatically severing said string close to said washer.

8. In a machine of the character described, means for stringing a washer comprising means for passing a loop of string through said washer and means for bodily removing said loop to a predetermined point spaced from said washer.

9. In a machine of the character described, means for feeding string comprising means for stringing a washer, means for gripping said string near the end thereof, and means for forwarding said washer.

10. In a machine of the character described, means for intermittently feeding string comprising oscillatory means for gripping said string, means for causing said gripping means to release said string and means for varying the position of one end of the arc through which said gripping means is oscillated for varying the length of string fed by said gripping means.

11. In a machine of the character described, means for stringing a washer comprising a reciprocating hollow needle adapted to have a string passed therethrough for forming a string loop in the opening of, and pendent from, said washer, on the downward movement of said needle, and means for reciprocating said needle.

12. In a machine of the character described, means for stringing a washer in space relation to the setting position, means for forwarding said washer and string to the setting position, means for delivering an eyelet into setting position, and means for flanging said eyelet for fastening said washer and string to an envelop.

13. In a machine of the character described, means for stringing a washer in space relation to the setting position, means for forwarding said washer and string to the setting position, means for delivering an eyelet into setting position, means for forming a bottom washer in the setting position, and means for flanging said eyelet for fastening said washer and string to an envelop.

14. In a machine of the character described, means for stringing a washer, means for forming a bottom washer at the setting position, means for fastening the washers

and string to an envelop, and means adjacent to the setting position for automatically severing said string close to the setting position.

5 15. In a machine of the character described, means for stringing a washer in space relation to the setting position comprising means for forming a string loop pendent from said washer, and means for 10 gripping said loop for drawing a predetermined length of string through said washer, and means for forwarding said washer and string to the setting position.

16. In a machine of the character described, means for stringing a washer in space relation to the setting position comprising means for forming a string loop pendent from said washer, and means for gripping said loop for drawing a predetermined 20 length of string through said washer, means for forwarding said washer and string to the setting position, means for forming a bottom washer at the setting position, means for fastening said washer and 25 string to an envelop, and means for severing said string.

17. In a machine of the character described, means for moving one washer at a time from a washer reservoir and for 30 forwarding said washer to the stringing position, and means for stringing said washer at the stringing position comprising means for forming a string loop pendent from the opening in said washer, and means for gripping said loop for drawing a predetermined 35 length of string through said washer.

18. In a machine of the character described, means for removing one washer at a time from a washer reservoir and for 40 forwarding said washer to the stringing position, and means for stringing said washer comprising means for forming a loop pendent from said washer and means for gripping said loop for drawing a predetermined 45 length of string through said washer, and means for severing said string.

19. In a machine of the character described, means for stringing a washer in spaced relation to the setting position, 50 means for forwarding said washer and string to the setting position, means for delivering an eyelet into setting position, means for forming a bottom washer at the setting position, means for flanging said eyelet for fastening said washer and string to an envelop, and means for severing said string.

20. In a machine of the character described, means for removing one washer at 60 a time from a washer reservoir and for forwarding said washer to the stringing position, and means for stringing said washer at the stringing position and for coacting with said forwarding means for forwarding the 65 strung washer to the setting position com-

prising a reciprocating hollow needle adapted to have string passed therethrough for forming a string loop pendent from the opening in said washer on the downward movement of said needle, and means for reciprocating said needle.

21. In a machine of the character described, means for stringing a washer comprising a reciprocating hollow needle adapted to have a string passed therethrough for 75 forming a string loop pendent from the opening in said washer, on the downward movement of said needle, means for reciprocating said needle, and means for gripping said loop for drawing a predetermined 80 length of string through said washer.

22. In a machine of the character described, means for removing one washer at a time from a washer reservoir and for forwarding said washer to the stringing position, means for stringing said washer comprising a hollow reciprocating needle adapted to have string passed therethrough for forming a string loop pendent from the opening in said washer, means for reciprocating said needle, and means for gripping said loop for drawing a predetermined 85 length of string through said washer, and means for severing said string.

23. In a machine of the character described, means for stringing a washer in space relation to the setting position comprising a reciprocating hollow needle adapted to have string passed therethrough for forming a string loop pendent from said washer, 95 means for reciprocating said needle and means for gripping said loop for drawing a length of string through said washer, means for forwarding said washer and string to the setting position, means for delivering an eyelet into setting position, 100 means for forming a bottom washer at the setting position, means for flanging said eyelet for fastening said washer and string to an envelop, and means for severing said 110 string.

24. In a machine of the character described, a washer reservoir, means for removing one washer at a time from said reservoir, and for forwarding said washer to 115 stringing position, and means for feeding string through said washer at the stringing position comprising means for forming a string loop pendent from said washer, means for gripping said string and for 120 drawing a length of string through said washer, and means for causing said gripping means to release said string at a predetermined point in the oscillation of said gripping means.

25. In a machine of the character described, means for forwarding a washer into stringing position, means for feeding string through said washer comprising means for forming a string loop pendent from said 130

washer, means for gripping said string and for drawing a length of string through said washer, and means for causing said gripping means to release said string at a predetermined point, means for delivering an eyelet into setting position, means for forming a bottom washer at the setting position, means for severing said string, and means for flanging said eyelet for fastening said washers and string to an envelop.

26. In a machine of the character described, a stepped slide for removing one washer at a time from a washer reservoir, means for stringing said washer, and means for reciprocating said slide for causing the rearmost step of said slide to carry a washer to the stringing position, for causing the forward step of said slide to carry a washer with the string passing therethrough to the setting position, and for retracting said slide whereby said stringing means coacts with said slide for forwarding a washer from the rearmost to the foremost step.

27. In a machine of the character described, means for feeding a predetermined length of string through an opening comprising a pair of spring tongs for gripping a string, means for oscillating the tongs with the string grasped therein to a predetermined point and for oscillating said tongs back to string gripping position, means for opening said tongs to release said string, and means for causing the withdrawal of said tong opening means at the string gripping position of said tongs.

28. In a machine of the character described, means for feeding string comprising a pair of spring tongs for gripping a string at a definite position, adjustable means for oscillating said tongs with the string grasped therein to various points as desired and for oscillating said tongs back to the string gripping position, and means for opening said tongs to release said string near the adjustable end of the oscillatory motion.

29. In a machine of the character described, a washer reservoir, a stepped slide for removing one washer at a time from said reservoir, means for stringing said washer comprising a reciprocating hollow needle adapted to have spring passed therethrough for forming a string loop pendent from said washer and means for reciprocating said needle, and means for reciprocating said slide for causing the rearmost step of said slide to carry a washer to the stringing position, for causing the foremost step of said slide to carry a strung washer to the setting position, and for retracting said slide whereby said stringing means coacts with said slide for forwarding a washer from the rearmost to the foremost step.

30. In a machine of the character described, a washer reservoir, a reciprocating

slide for forwarding one washer at a time from said reservoir to the stringing position and for forwarding another washer at the same time from the stringing to the setting position, a reciprocating hollow needle adapted to have string passed therethrough for forming a string loop pendent from said washer at the stringing position, a pair of spring tongs for gripping said loop, means for oscillating said tongs with the string grasped therein to a predetermined point and for oscillating said tongs back to string gripping position, means for opening said tongs to release said string, and means for causing the withdrawal of said tong opening means at the string gripping position of said tongs.

31. In a machine of the character described, a washer reservoir, a reciprocating slide for forwarding one washer at a time from the reservoir to the stringing and setting positions, a reciprocating hollow needle for forming a string loop pendent from said washer at the stringing position, a pair of spring tongs for gripping said loop to draw a length of string through said washer, means for opening said tongs at a predetermined point for causing said tongs to release said string, means for withdrawing said tong opening means at the string gripping position of said tongs, a pair of shearing blades, means for bringing said blades together for severing said string, means for forming a bottom washer, and means for fastening said washers and string to an envelop.

32. In a machine of the character described, a washer reservoir, a reciprocating slide for forwarding one washer at a time from said reservoir to the stringing position and for forwarding another washer at the same time from the stringing to the setting position, means for stringing a washer at the stringing position, a pair of shearing blades and means for operating said blades for severing said string.

33. In a machine of the character described, a reciprocating slide for forwarding a washer to the stringing position and for forwarding another washer at the same time from the stringing to the setting position, means for stringing a washer at the stringing position, means for delivering an eyelet into setting position, means for forming a bottom washer at the setting position, a pair of shearing blades for severing said string, and means for flanging said eyelet for fastening said washers and string to an envelop.

34. In a machine of the character described, means for stringing a washer at a point in space relation to the setting position, means for forwarding said washer and string to the setting position, a pair of tongs for gripping the string at the stringing position.

tion for drawing a length of string through said washer, means for causing said tongs to release said string at a predetermined point, a pair of shearing blades and means 5 for operating said blades for severing said string.

35. In a machine of the character described, means for stringing a washer in space relation to the setting position, means 10 for forwarding said washer and string to the setting position, means for delivering an eyelet into setting position, means for forming a bottom washer in the setting position, a pair of shearing blades, springs normally 15 holding said springs apart, reciprocating means for operating said blades for severing said string, and means for flanging said eyelet for fastening said washer and string to an envelop.

20 36. In a machine of the character described, means for stringing a washer in space relation to the setting position comprising means for forming a string loop pendent from said washer and means for

gripping said loop for drawing a predetermined length of string through said washer, and a stepped slide for forwarding one washer at a time to the stringing position and for forwarding another washer at the same time from the stringing to the setting 30 position.

37. In a machine of the character described, means for stringing a washer comprising means for forming a string loop pendent from said washer and means for 35 gripping said loop for drawing a length of string through said washer, a stepped slide for forwarding one washer at a time to the stringing position and for coacting with said stringing means for forwarding another 40 washer at the same time from the stringing to the setting position, a pair of blades for severing said string, and means for fastening the washer and string to an envelop.

Signed at New York, in the county of 45 New York, and State of New York, this 16th day of February, A. D. 1920.

ABRAHAM NOVICK.
